F. S. Giles,

United States Patent Office.

FAYETTE S. GILES, OF NEW YORK, N. Y., ASSIGNOR TO GILES, WALES & CO., OF SAME PLACE.

Design No. 3,885, dated March 8, 1870.

DESIGN FOR THE TOP-PLATE, BARREL-BRIDGE, AND COCK FOR WATCHES.

The Schedule referred to in these Letters Patent and making part of the same.

To all whom it may concern:

Be it known that I, FAYETTE S. GILES, of the city, county, and State of New York, have invented a new Design for the Top-Plate, Barrel-Bridge, and Cock for Watches; and I do hereby declare that the following is a full, clear, and exact description of the same, reference being had to the accompanying drawings forming part of this specification, in which—

Figure 1 is a top view of the parts of the watch included in my design.

Figure 2 is a profile of the same perpendicular to fig. 1, in the plane indicated by the line x x , in fig. 1.

Similar letters of reference indicate corresponding parts in both figures.

A is the top-plate;

B, the cock;

C, the barrel-bridge;

D, the arbor-cup; and

E, the ratchet-cap.

The top-plate A in its plan conforms externally to the circle of the watch-case. It is of crescent-like form, with one of the horns of the crescent cut off in a straight line, a , and with a central circular projection at b , to surround the center spindle of the watch.

On one side of b it is hollowed out in arc-form, as shown at c , to conform to the balance, and on the

other side of b it is hollowed out, as shown at c' , in the form of an arc concentric with the winding-arbor.

The cock B has the portion by which it is attached made to conform externally to the circle of the case, and is curved in the form of a hollow arc, as shown at d d , to form parts of the same circle with the arc c , and conform to the balance.

The barrel-bridge is straight on both sides for the greater portion of the length, having its ends curved to conform to the case, and uniting at a with the straight end of the top-plate, and it has the end next the cock widened, to unite with the cock in the line e , which is radial to the center of watch, and this widened part is hollowed out internally in arc-form, as shown at f f , to conform to the arc c' of the top-plate and concentric with the winding-arbor.

What I claim, and desire to secure by Letters Patent, is—

The design and configuration of the top-plate, cock, and barrel-bridge of a watch, as herein described and represented in the accompanying drawings.

F. S. GILES.
